Frode Hansen, 12 Links Road, Epsom, Surrey, England
Continuation-in-part of application Ser. No. 147,344,
Oct. 24, 1961. This application Feb. 24, 1965, Ser.
No. 434,859

Claims priority, application Great Britain, Oct. 25, 1960,
36,636/60; Oct. 10, 1963, 40,094/63
5 Claims. (Cl. 46—26)

This application is a continuation-in-part of application Ser. No. 147,344, filed Oct. 24, 1961, now abandoned.

This invention relates to a set of polygonal members for erection into a constructional unit and which can be used for instructional purposes or in the form of a toy.

In civil engineering a complicated concrete structure can be split into a number of simpler units capable of being prefabricated on a mass production scale, and which can be joined together to form monolithic structures by stress members so that the compression thereby applied through the built-up structure results in the joints between the units resisting the forces acting on the final structure in any direction.

The main object of the present invention is to provide a set of members for erection into a constructional unit such that the members of the set can be prefabricated on a mass production basis and can be employed for erection of constructional units of a wide variety of shape and design.

According to the present invention a set of elements for erection into a constructional unit comprises a number of polyhedral elements each having an aperture extending between and through a pair of generally opposite outer faces thereof, a joint element disposable in contact with contiguous outer faces of any two juxtaposed polyhedral elements and having on each face a profile engageable in contiguous profile of each polyhedral element, terminal elements engageable with the end polyhedral elements of the assembled unit, and a stressing element or elements locatable with respect to the assembled elements to maintain all the assembled elements under compression, thereby forming a constructional unit.

Preferably the faces of each joint element engageable in the polyhedral elements have a similarly shaped profile to the contiguous faces of the polyhedral elements. The stressing element may be formed by an elongated element of a length sufficient to enable it to be located within the assembled elements under tension so that it will maintain all the assembled elements under compression.

The terminal members preferably each have a profiled face similar to the profile of the joint element and, so disposed on said face as to be located in the longitudinal axis of the assembled unit, a member to which the ends of the stressing member can be connected under tension to compress the assembled elements together.

The profile on the faces of the polyhedral joint and terminal elements are preferably in the form of interengaging recesses and protrusions of a construction which will prevent rotation of the assembled elements about the longitudinal axis thereof.

The said recesses and protrusions may be polygonal or otherwise non-symmetrical about the said axis and a number of the recesses and protrusions may be formed on each element face.

At least some of the polyhedral elements may have two or more pairs of opposing apertured faces, the apertures on all the faces communicating with the aperture

2

through the element, which may be a hollow interior of the element, and constituting the said profiles.

The opposing profile faces of the polyhedral elements may be parallel or at such angles to each other as to ensure that when the stressing element is secured under tension within the remaining elements said stressing element will maintain the remaining elements under compression thereby forming a constructional unit.

The polyhedral elements are each preferably in the form of hollow frames having a plurality of open frame-like faces, the inner periphery of each frame forming a profiled recess to receive a similarly shaped raised profile on a joint element.

The stressing element may comprise a member passing through the apertures in the remaining assembled elements, means being provided to cause a tensile force in the stressing element to maintain the remaining assembled elements in compression. In another construction the stressing element comprises a loop of nylon, rubber or like strand or strip, and blocks, rods or the like preferably notched or apertured to receive the loop ends are disposed at least one at each loop end, the loop being of such a length for a predetermined number of the remaining elements as to be insertable through said elements and twistable to exert a compressive force between the assembled elements through the blocks, rods or the like.

In order that the invention may be more clearly understood some embodiments thereof will now be described, by way of example, with reference to the accompanying drawings, in which:

FIGURE 1 is a perspective view of a polyhedral element for use as one of the set of members;

FIGURES 2 and 3 are perspective views of alternate forms of polyhedral elements;

FIGURE 4 shows a perspective view of a joint element;

FIGURE 5 is a similar view to FIGURE 4 of an alternative form of joint element;

FIGURE 6 is an exploded view of the terminal elements, a stressing element and the members by which the terminal elements are secured in the erected constructional unit;

FIGURES 7 and 8 are perspective views of tools used in tensioning the stressing element during erection of the constructional unit;

FIGURE 9 is a perspective view of the set of members being assembled into two forms of the constructional unit, which are in fact connected together;

FIGURE 10 shows another form of stressing element;

FIGURES 11A and 11B show respectively the parts of yet another form of stressing element, and, such parts assembled and twisted to indicate how the tension is applied by the stressing element to the assembled elements;

FIGURES 12 and 13 show respectively a construction of a joining element, the method of locating it to hold the polyhedral elements together;

FIGURE 14 is a sectional view of a locking element assembled with the joining member of FIGURES 12 and 13;

FIGURE 15 shows a perspective view of the locking element of FIGURE 14 which is adapted to be inserted in the joining member of FIGURES 12 and 13 to prevent accidental dislodgment of the joining member;

FIGURE 16 is a view of polyhedral elements which can be united to form a single polyhedral element;

FIGURES 17 and 18 show the parts of another form of polyhedral element;

FIGURE 19 shows a manner of assembling the elements as in FIGURES 17 and 18 so that the joints be-

tween elements and the parts of the elements are staggered,

FIGURES 20-29 show further forms of polyhedral elements which can be used in the set; and

FIGURE 30 shows several polyhedral elements interengaged to form part of a constructional unit, the terminal element and tensioning tool being shown detached for clarity.

In the drawings the same references have been used to designate the same or similar parts.

Referring to the drawings a set of elements for erection into a construction unit such as is shown in FIGURE 9 comprises a number of polyhedral elements 1, 2 or 3, each having an aperture therethrough constituted by a hollow interior extending between and through a pair of generally opposite outer faces 4, 5; in FIGURES 1 and 2 the faces 4 and 5 are parallel but, as shown in FIGURE 3, they may be at an angle other than 90° to the other face of the polyhedral element. A joint element 6 is shaped for disposition in contact with the contiguous outer faces, e.g. 4 or 5, of any two juxtaposed elements 1, 2 and 3 and each has a face 7 profiled to engage in a contiguous profile 8 comprising first connection means, preferably similarly shaped thereto, in each of the elements 1, 2 or 3.

Terminal elements 9 (FIGURE 6) are provided for engagement with the end polyhedral elements of the assembled constructional unit and each terminal element 9 has a profiled face 10, preferably similarly shaped to the face 7 of the element 6 as shown, for engagement in the shaped profile 8 of the polyhedral element. All the profiled faces 7, 8 and 9 are preferably as shown in the drawings of the same dimensions of length and breadth whereby all the elements are capable of being interchanged, thereby enabling the parts to be built-up in a number of different constructional units.

A stressing element 101 (FIGURE 6) is provided including a resilient portion 11 at one end or, as shown in FIGURE 6, at both ends. The stressing element is an elongated element of a length sufficient to suit a predetermined number of polyhedral elements and their interposed joint elements so that, when connected as herein described, the stressing element being under tension will maintain all the elements under compression comprising second connection means.

To this end the stressing element is used with fixing members 12 each having a head 13 and a shank screw-threaded as at 14 for threading into the portion or portions 11 of the stressing element. The joint elements and the terminal elements have central apertures which, in the forms shown in FIGURES 4, 5 and 6, extend as slots 15 to one edge of the elements to facilitate assembly of the set and through which the members 12 pass. In erecting the set into a constructional unit the fixing member 12 is engaged into the upper ends of the members 11 of the stressing element and, by screwing the fixing members into the portions 11, the heads 13 will engage the terminal members 9, thereby, as they are screwed further, tensioning the stressing element.

The manner of erecting the set of elements into a constructional unit is shown in FIGURE 9. In FIGURE 9 a vertical unit is shown being assembled and, attached to one face of the central polyhedral element of the form shown in FIGURE 2, has built onto one side a second constructional unit employing the polyhedral element of FIGURE 3 and the joint element of FIGURE 5 and a further joint element 16, this additional unit being of arcuate form and connected to the first unit through the joint element 16.

It will be seen that the polyhedral elements are threaded onto the stressing element 101 and, while they are spaced apart, the joint elements 6 are slipped onto the stressing element, the terminal elements 9 are slipped over the fixing members 12, one on each end, which are being screwed into the portions 11 of the stressing element. By

75 screwing the fixing members 12 into the portions 11 the elements are all brought into surface contact, the shaped profiles of the various elements fitting one into the other. Ultimately, when the fixing members have been screwed firmly into position the whole will be a stable constructional element in equilibrium with the stressing element in tension disposed axially through all the members to hold the assembly in compression so that the erected constructional unit can resist normal forces applied to the unit longitudinally or transversely at any angle to any face thereof.

The erection of the second constructional unit shown in FIGURE 9 is effected in a similar way to that described for the vertical unit in that figure.

15 While the polyhedral elements have been shown as cubes and parallelepipeds or truncated pyramids, they may have any polyhedral shape, for example hexagonal or pentagonal. Alternatively the polyhedral elements may be circular about an axis on which the stressing element will ultimately lie and their tops and bottoms may be formed with the profiled surfaces for engagement by the jointing and terminal elements. These profiled faces may if desired be flat, as shown in the drawings, or they may be curved, corrugated or, if other surface shapes are 20 desired, the profiled surfaces of all the elements which are 25 to be connected together may be similar in shape.

As to the stressing elements, these may have the fixing member integral with one end thereof or both ends may be separate members as shown in FIGURE 6.

30 The tools shown in FIGURES 7 and 8 have shaped sockets 17 for engagement with the heads 13 of the fixing members.

The stressing element may be made as shown in FIGURE 10, with a string 101 of a strong flexible material 35 attached to two fixing members shown as eyebolts 11a and the tension obtained by tightening screw threaded headed bolts or nuts (not shown) on the eyebolts 11a on the outside faces of the terminal elements.

Another form of stressing element is shown in FIGURES 11A and 11B, the element being a piece 101 of 40 strong flexible strand, e.g., nylon, made into a loop by means of a simple knot. Two short pins indicated at 11b with a shallow groove 11c in the middle to locate the strand anchor the stressing element to the terminal element. The tension is obtained by turning one of the anchor pins 11b round to twist the strands of the loop, as seen in 45 FIGURE 11B. The friction between each anchor pin and the anchor plate will, when the tension in the element 101 is sufficient, prevent the stressing element from unwinding 50 and thus lock it under tension with the remaining elements in compression.

For shorter and smaller structures, or where the joints are automatically under compression it will be convenient to have a method of assembling whereby the elements 55 can be joined one by one with the joining members of resilient material located in tension between each two adjoining elements, but still giving a stable connection able to resist forces on the elements in all directions. The same method can also be used for the larger structures, such as 60 shown in FIGURE 9 with a stressing element such as shown in FIGURES 6, 10 or 11 threaded through the assembled elements, as by passing them through apertures in the joining members, and tensioned to give added stability.

65 Referring to FIGURE 12 this shows a joining member 161 shaped to fit into the hollow interiors of the polyhedral elements 2a shown as having plate like portions, but the member 161 has protruding edges to grip on the faces 16a of the contiguous elements 2a. FIGURES 13 and 14 show how the member 161, due to spring action, can be forced into location to hold the elements 2a in compression. FIGURE 15 shows a locking element 18 70 substantially cubic in form, having a slight taper on two opposite sides.

In assembling the elements described with reference to FIGURES 12-15, when the two elements 2a have been disposed close together, the protruding edges 16b of the member 16 will slide in over the sides of the faces of the apertures in the elements 2a and then spring back to the natural shape to engage the faces 16a. The locking element (FIGURE 15) is thereafter pressed into position in the cavity in the member 16. Friction will prevent the locking element sliding out of the member 16, and with the former in position, no springing action of the member 16 is possible. The two polyhedral elements 2a cannot be pulled apart nor move relative to each other.

A stressing element such as that of FIGURES 6 or 10 and 11 may be threaded through apertures 17, 17a being provided in the member 16 and element 18 and the assembly of a member 16 and a locking element 18 can be used as terminal element or anchor plate.

Referring to FIGURE 16 this shows a polyhedral element similar to that shown in FIGURE 1 and is made up of a main polyhedral element having a rectangular frame piece 20 from the corners of which elongated pieces 21 extend at right angles thereto, and a second and separate rectangular piece 22 provided with apertures 23 into which dowels 24 on the ends of the pieces 21 frictionally engage to form an element similar to that in FIGURE 1. FIGURE 16 also shows a further piece 25 similar to 20, 21 which by its dowels 24 may be connected to the piece 20 or the piece 22, in the former case forming an element similar to that shown in FIGURE 2. The polyhedral elements of FIGURES 3, and other shapes referred to herein, may be made up of pieces in a similar manner to that shown in FIGURE 16. The elements of FIGURE 16 have the advantage of being easily moulded in synthetic plastic materials. They can be assembled with stressing members as described with reference to FIGURES 1 to 15.

The elements may be of any desired size for use as a plaything for example or for such uses as tutorial equipment or for experimental purposes in building construction.

Referring to FIGURES 17, 18 and 19, these show an element similar to that of FIGURE 16 but with several leg-like portions 26 extending away from a frame-like portion 27 and having pins 28 which engage in holes 29 in the frame-like portion 30 to form elongated polyhedral elements with several apertures in the longitudinal sides. These elements can be made up by making the portion 30 coincident with the portion 26-27 but as seen in FIGURE 19 the portions 30 may be separable and may extend over two separable portions 26 and 27 so that they embrace and reinforce the joint between the two portions 26-27. The leg portions 26 at one end of the frame portions 27 have extensions 31 on the outer ends of which are sideways directed lugs 32 so shaped that two elements 26-27 can be joined as in FIGURE 19 by sliding the extensions 31, 32 between the end leg portions 26 so that they enter the hollow interior of the adjacent elements 26-27 and extend round the leg portions 26 thereof to grip the two elements 26-27 together whereafter the portions 30 are fitted on to the pins 28. By this means additional means are provided co-operating with the stressing element (omitted in FIGS. 17 and 18) to form the structural element. The extensions 31, 32 can also be used to connect branch structures on to a main longitudinal structure so that much larger structures can be built up of the polyhedral elements which may be added to by further polyhedral elements from time to time if desired.

Examples of some further configurations of building elements which can be used in the set are shown in FIGS. 20-29.

FIG. 20 shows a polyhedral element in which tapered sockets 33 are formed in upstanding cylindrical projections 34 on the end face 35 of the element. A cross-section along the line X-X of FIG. 20 looking in the direction of the arrows is provided in FIG. 21, showing more clearly

the taper of the sockets and the dowels 36 for engagement in sockets in contiguous elements.

FIG. 22 shows a polyhedral element of frame-like construction having legs 37 with a dowel 36 on the free extremity of each leg, the end face 39 of the element being apertured with curved shouldered projections 38 extending along two opposite faces of the aperture. The element of FIG. 22 can be completed into a six sided frame by a rectangular frame such as 22 in FIG. 16, the dowels 36 engaging in the frame apertures 23 (FIG. 16).

FIG. 23 shows a polyhedral element of general open box-like shape, the outside end face of the element having a dowel 36 near each of its corners. A cross-section of FIG. 23 along the line Y-Y looking in the direction of the arrows is shown in FIG. 24.

FIG. 25 shows a polyhedral element of the same general configuration as that in FIGS. 23 and 24, except that sockets 40 instead of dowels are formed in the corners of the end face 41 of the element.

FIG. 26 shows a generally wedge-shaped element used mainly for disposition between adjacent polyhedral elements when it is desired to form a slightly curved constructional unit. This element is provided on opposite faces with dowels 36 and sockets 40 respectively.

FIG. 27 shows an element for use primarily in retaining the end of a stressing element at the extremity of a built-up unit. This element has an upstanding circular boss 42 for engagement in a recess of a polyhedral element allowing the former to be rotated to tension the stressing element and the corners 43 are cut away to allow the element, after stressing the tensioning element, to be located within a recess, not shown, of the adjacent polyhedral element so that the retaining element is then prevented from rotating.

FIG. 28 shows a further form of element for retaining a stressing element, but having an upstanding rectangular profile 44 on one face for engagement in a recessed face of a polyhedral element to prevent rotation of the retaining element.

FIG. 29 shows a four-sided element having sockets 40 in each of its corners to receive the dowels of an element such as that shown in FIG. 22 for example, whereby a complete polyhedral element is formed.

FIG. 30 shows a number of polyhedral elements interengaged to form part of a constructional unit. The terminal retaining element 45 similar to that in FIG. 27 is shown detached for clarity with the stressing element 46 threaded therethrough and continuing through the centre of the unit. It will be seen that by engaging the dowels 47 of the tool 48 in a pair of sockets 49 or 50 in the element 45, the latter may be rotated to twist and so tension the stressing element, the other end of which will be anchored at the other end of the unit (not shown).

Most of the elements shown in FIGS. 20-30 are provided with two eccentric pairs of holes 49, 50 and a central hole 51 in one face, thus enabling a plurality of stressing elements to be passed therethrough. Each of the elements of FIGS. 20-29 may have a similar arrangement of holes as shown. Such an arrangement helps to prevent disengagement of adjacent elements when forces transverse to the longitudinal axis of an assembly of elements are applied to the assembly. Moreover by having a number of tensioning elements through holes 49, 50, 51 in alignment in the assembled elements, this prevents a tendency in the assembly to curve lengthwise due to the tension and ultimately to collapse. Also the non-central holes provide sockets into which the dowels on the tensioning tool can be engaged to twist the stressing element.

We claim:

1. A set of elements for erection into a constructional unit, said set comprising a number of hollow, polyhedral elements each having an aperture extending through each face thereof and communicating with the hollow interior, the apertures in said faces being such that each face is frame-like having leg-like portions forming the

sides of the frame, connecting means including connecting elements between such polyhedral elements and disposable in contact with and fitting into said frame-like face apertures with portions extending into the hollow interior of the polyhedral element and gripping round the leg-like portions of the frame-like faces to form an assembly of said polyhedral elements, said connecting elements being flexible for pushing into the apertures, insert means for maintaining said connecting elements rigid when gripping said leg-like portions, said connecting elements and insert means each having a central passage therethrough, and second connecting means including terminal elements rotatably engageable with the end polyhedral elements of the assembled unit, and at least one stressing element having a twistable portion passing through the hollow polyhedral elements and said central passages and being non-rotatably fastened to said terminal elements which are rotatable to twist said twistable portion of the stressing element to maintain all the assembled elements under compression thereby forming a constructional unit.

2. A set according to claim 1 wherein each said connecting and polyhedral element is shaped with the portions within a polyhedral element not interfering with the similar portion of another connecting element extending through another aperture to the hollow interior of the same polyhedral element thereby enabling the assembly of elements to be extended freely in all directions through some or all of the aperture faces of each of the polyhedral elements.

3. A set according to claim 1, wherein each said connecting element is provided with said portions engaging into the apertures and gripping around at least two opposite leg-like portions of a contiguous one of said polyhedral elements to provide an assembly of elements.

4. A set according to claim 1 wherein at least some of the polyhedral elements have a framewise side portion

5 with legs extending from at least some corners of said frame-like side portion, the ends of said legs being formed as pins, corresponding sockets being formed in contiguous elements to receive said pins thereby joining said contiguous elements to form said last mentioned polyhedral elements of a different shape than the others of said polyhedral elements.

10 5. A set according to claim 1 wherein at least some of the polyhedral elements have a part including a frame-like side portion with legs extending from the sides and corners of said side portion, the end of each said legs being formed as a pin, the remaining parts of said last mentioned polyhedral elements being flat and framewise and having sockets to receive said pins so that two such parts can be pushed together to form one closed polyhedral element with framewise sides on all faces and at least one of said faces having extensions with angularly directed lugs to grip around the legs of a contiguous one of said polyhedral elements when assembling a structural unit.
